UNITED STATES PATENT OFFICE.

JOHN H. FLORY, OF COLUMBUS, OHIO, ASSIGNOR TO THE JEFFREY MANUFACTURING COMPANY, OF COLUMBUS, OHIO, A CORPORATION OF OHIO.

ELECTRIC LOCOMOTIVE.

1,203,999.

Specification of Letters Patent.

Patented Nov. 7, 1916.

Application filed December 27, 1913. Serial No. 809,087.

To all whom it may concern:

Be it known that I, JOHN H. FLORY, a citizen of the United States, residing at Columbus, in the county of Franklin and State of Ohio, have invented certain new and useful Improvements in Electric Locomotives, of which the following is a specification, reference being had therein to the accompanying drawings.

10 The invention relates more particularly to locomotives adapted for use in coal and other similar mines, and especially to locomotives adapted and intended for collecting cars from the points where they are loaded and assembling them at convenient places to be formed into trains, which trains are subsequently hauled from the mine by other locomotives.

In a coal mine there are ordinarily one or 20 more main passages or entries from which extend lateral branches or side entries. From these branches or side entries are driven rooms in which the principal mining operations are carried on. Tracks are laid 25 along the main entries and along the side entries and branches extend from the side entries into the rooms. Adjacent the tracks in the main and side entries there are usually provided trolley wires for the transmission 30 of power to locomotives on these tracks; but on account of the temporary and constantly varying character of the tracks in the rooms, it is usually found impossible or undesirable to extend the trolley wires into 35 the rooms. Numerous mechanisms and systems have been devised and used for enabling the locomotives to handle the cars and move them along the temporary tracks in the rooms. The most usual means comprises 40 a flexible conductor cable, one end of which is connected to the trolley wire in the entry, and the other end of which is carried by the locomotive. By means of current transmitted through this cable the locomotive is 45 enabled to advance into the rooms over the temporary tracks therein. The locomotive is provided with a reel upon which the cable is carried and from which it is paid off as the locomotive advances, and upon which it 50 is wound as the locomotive returns. Locomotives provided with flexible conductor cables and with reels therefor, while satisfactory under many conditions, have, under

other conditions, serious disadvantages. The cable mechanism, including the cable itself, 55 the reel and the driving mechanism therefor, is at best quite heavy and bulky; and, because of the necessary weight and size, the amount of cable which can be carried is narrowly limited. Obviously a locomotive 60 provided with a cable and reel is rigidly limited as to its range of travel away from the entry and, in many instances, it is desirable for the locomotive to travel farther than is permitted by the length of cable 65 which it is practical to carry. Another serious objection to a conductor cable as commonly used is that the insulation frequently becomes worn so as to expose the conductor which comes in contact with the track rails 70 or other conductors, and causes a flash or spark which is liable to fire any explosive mine gases which may be present. The expense of maintenance of a cable reel locomotive is necessarily great as certain of the 75 parts, especially the cable, must frequently be replaced. The cable is subjected not only to the ordinary wear resulting from winding and unwinding and from contact with the ground, but is also frequently injured by 80 accident as, for instance, when it is run over by the track wheels of the locomotive. Having in mind these and other advantages incident to locomotives having cables and reeling mechanism, I have provided a locomotive in which there is a storage battery and means for utilizing the current in the battery to drive the locomotive when current from a trolley wire is not available.

I am aware that it has been heretofore 90 proposed to provide locomotives and other vehicles with storage batteries which can be used alternately with a trolley or other equivalent mechanism but, so far as I am aware, in these earlier proposals it was contemplated to use a single motor for utilizing the trolley current and for utilizing the battery current. In a mine the cost of the trolley wires makes it necessary to use relatively small wires and a current of correspondingly high voltage; and, because of the restrictions of space, it is impossible to provide a battery which will furnish current at the voltage necessary for the trolley wires. This difficulty I meet by providing two 100 motors, one having a winding adapted for 105

the high voltage of the trolley wire current and the other adapted for the lower voltage of the battery current. And by preference and in order to still further economize in space, I combine these two motors into a single mechanical unit by placing the two sets of armature windings and the two commutators upon the same shaft and making use of the same field windings. I further-
 10 more provide means whereby the low voltage motor may be driven by the high voltage motor and thus used as a dynamo for the charging of the battery. In this way the battery can be charged while the locomotive is in operation on current received from the trolley wire. I preferably provide also a clutch mechanism whereby the two motors can be disconnected from the locomotive track wheels and operated independ-
 15 ently to charge the battery when the locomotive as a whole is stationary.

The principal objects of my invention are, therefore, to provide a locomotive having the features above described.

20 Other objects will be made clear from the following specification and from the accompanying drawings which show the embodiment of the invention which I now deem preferable.

25 Of the drawings, Figure 1 is a side elevation of a locomotive embodying my invention. Fig. 2 is a plan view of the locomotive shown in Fig. 1, the top cover plate being removed to show the mechanism more clearly. Fig. 3 is a fragmentary sectional view through the motor and associated parts taken along the line 3—3 of Fig. 4. Fig. 4 is a side elevation of the parts shown in Fig. 3. Fig. 5 is a horizontal sectional view taken through the controller. Fig. 6 is a diagram of the electrical connections.

30 Referring to the drawings, the main frame of the locomotive comprises the two side members 1 and 2 which are joined at the ends by the members 3 and 4. To the end members 3 and 4 are attached draw bars 5. The main frame is mounted on track wheels 6 and 7 which are fixed, respectively, to the axles 8 and 9.

35 The motor unit is indicated as a whole by 10, and is carried by bearings 11 engaging the axle 8 and by a spring 12^a engaging the cross bar 12. The armature pinion 13 of the motor unit meshes with the intermediate gear 14 carried by the intermediate shaft 15. This shaft is supported in bearings 16 and 17 carried in the motor frame. Mounted for free rotation on the shaft 17 is a pinion 18. The pinion 18 is provided with clutch teeth adapted to mesh with similar teeth on the clutch member 19 splined to the shaft 15. This clutch member 19 can be moved by means of the forked bell-crank 20 and the link 21 into or out of engagement with the pinion 18, thus connecting or discon-

necting the pinion from the shaft 17. The link 21 extends to a point within reach of the locomotive operator. The pinion 18 meshes with a gear 22 secured to the axle 8 and it will be seen that through the gears 70 15, 18 and 22 power can be transmitted from the motor to the axle. The two axles are connected together by means of connecting rods 23, 23.

24 represents the trolley mechanism adapt- 75 ed to contact with the usual trolley wire.

25 represents the storage battery adapted to supply current when no trolley wire is available.

26 is a controller for properly connecting 80 the trolley mechanism, the battery and the motor unit, and will be described below in detail.

The locomotive is provided with a suitable 85 brake mechanism the details of which form no part of this present invention. The brake mechanism is controlled by means of a hand wheel within reach of the operator. At each end of the locomotive there is a headlight 28 and each headlight is provided with two 90 lamps, one adapted for the high voltage current of the trolley wire and the other adapted for the low voltage current of the battery. The high voltage lamps are indicated by 29, 29 in the diagram of electrical connection in Fig. 6, and the low voltage lamps are indicated by 30, 30 in the said diagram. At 31 and 32 are resistance grids which will be referred to below in connection with the diagram of electrical connections. At 34 100 is an automatic contact switch which will be referred to below. This switch is protected by a casing 33.

As stated at the outset, I provide two motors, one for the high voltage trolley wire 105 current and the other for the low voltage battery current; and by preference, in order to economize in space and weight, I combine these two motors into a single mechanical unit which, as before stated, is indicated in the drawings by 10. Referring especially to Fig. 3, 35 represents the common armature shaft of the two motors, this shaft being mounted in ball bearings 36 and 37 supported in recesses in the end walls 38 and 39 of the motor unit. To this armature shaft is keyed a non-magnetic sleeve 40 upon which is fixed a magnetic core 41 made up of thin steel disks clamped together by the end flanges 42 and 43.

110 Secured to one end of the armature shaft 35 is the commutator 44 of the high voltage motor. Formed in the periphery of the magnetic core 41 are slots. In each slot there is laid a coil or winding 44^a. The several windings 44^a are connected, respectively, to the bars of the commutator 44. Brushes 44' and 44'' (indicated in Fig. 6) engage the commutator 44 and complete the circuit through the armature. At the other 115 120 125 130

end of the shaft 35 is the commutator 45 of the motor for the low voltage current. Also positioned in each slot of the core 41 is a coil or winding 45^a. The several windings 5 45^a are connected, respectively, to the bars of the commutator 45. Brushes 45' and 45'' (indicated in Fig. 6) engage the commutator 45 and complete the circuit through the low voltage armature. 10 The two motors by preference make use of the same field windings. As shown, there are four poles of which two are salient and two are consequent. In the construction shown the salient poles are arranged at the 15 top and the consequent poles at the sides and therefore only consequent poles show in Fig. 3. The field winding is of the series parallel type, each winding having two coils 48 and 49 or 48' and 49'. The coils 48 and 20 48' are series connected and the coils 49 and 49' are shunt connected.

The battery 25 is preferably inclosed in a casing 50 and I provide means whereby air can be forced through this casing to 25 ventilate it. Preferably the ventilating means consists of a fan 51 mounted on the end of the armature shaft 35 and operating in a casing 52. The casing 52 has an outlet 53 which is connected with the battery casing 50 by means of a flexible tube 54. At 55 is a passageway through which air passes from the fan casing into the casing of the motor to ventilate it.

The controller 26 can, as concerns its mechanical construction, be formed in any of a number of ways. I prefer, however, to use a controller similar to the controllers commonly used at present upon locomotives of this general class. The controller as 40 shown in the drawings is provided with a commutating cylinder by means of which the current to the motors is controlled, and a connecting and reversing cylinder by means of which the motor connections are reversed 45 and by means of which the connections to the trolley mechanism or to the battery are made or broken. The reversing and connecting cylinder as shown is composed of a cylinder 57 formed of some insulating material such as wood, and it is mounted upon a vertical shaft 58 held in suitable bearings. The shaft 58 is provided with a handle 59 for turning it. Fixed to the cylinder 57 are contact plates arranged in vertical rows 50 A, B, C and D which are adapted to contact with brushes E to form the necessary connections to be fully described below. Auxiliary brushes I' and I'' are located 55 diametrically opposite to the main brushes E for a purpose to be described.

The commutating cylinder comprises three metallic contact sections F, G and H insulated from each other and from the shaft 60 upon which they are mounted. The 60 shaft 60 is mounted for rotation in suitable

bearings and is provided with a handle 61 by means of which it may be turned. Suitable brushes K are arranged to contact with the sections. In order to prevent destructive arcing at and between the several 70 brushes, a magnetic blow-out mechanism is provided comprising the magnetic pole piece 62 which is excited by the magnetic coils 63 and 64. The brushes K are further protected by means of plates of non-combustible 75 insulating material 65, 66 and 67 which surround them and separate them from each other forming arcing chambers.

For convenience in removing and replacing the trolley mechanism upon the frame 80 of the locomotive, the conductor cable, by which the current is led from the trolley wire to the locomotive wiring, is provided with a separable plug and socket device which is shown conventionally at 68 in the 85 diagram in Fig. 6. Similar plug and socket devices 69 and 70 are provided in connection with the storage battery. 71 is an ampere-hour meter which is provided to indicate the condition of the battery. 90

Referring now to the diagram of electrical connections appearing in Fig. 6, let it be supposed that it is desired to run the locomotive ahead while receiving current from the trolley wire. The operator first 95 turns the handle 59 to the "trolley-ahead" position which brings the contacts C into engagement with certain of the brushes of the series E. The operator then turns the handle 61 to bring the contacts F 10 and H and finally the contact G into engagement with certain of the brushes of the series K.

As soon as the section F engages the brushes K¹ and K² and the section H engages the brushes K¹¹ and K¹², the circuit through the high voltage motor is completed and current flows from the trolley through the plug and socket device 68 and through the fuse 72 to the brush E¹; from the brush E¹ to the brush E² and to the point 73 where it divides part going through the coil 63 and part through the coil 64; from the coils 63 and 64 the current flows through the brush K¹, to the contact section F, to the brush K² and to the brush K¹²; from the brush K¹² through the contact section H to K¹¹ and to the point 74. From the point 74 a part of the current passes through the resistance 31 to the point 75 and from that 115 point to the brushes E⁵ and E⁷; from the brush E⁷ the current flows through the motor brush 44', the motor commutator and armature 44, the motor brush 44'' and to the brush E⁴; from the brush E⁴ the current flows to the brush E⁸ and through the motor field coils 48 and 48' to the point 76; from the point 74 a shunt current passes 120 through the motor field coils 49 and 49' to the point 76; from the point 76 to the cur- 125 65

rent flows to the brush E^9 , to the brush E^{10} and to the ground. At 77 there is connected a branch wire which conducts current to the two lamps 29, 29 and to the ground, these two lamps being located each in one of the headlights 28. As the commutator cylinder of the controller is moved to bring the contact section H successively into engagement with different brushes of the series K, the resistance 31 is gradually cut out from the main circuit thus reducing the resistance to the flow of current through the armature of the motor 44.

At 78 there is led off from the main circuit a branch wire in which is located a manually controllable switch 79. From the switch 79 the current passes through the winding of a solenoid forming a part of the automatic switch 34 and to the ground. The solenoid is provided with a core which carries a contact bar 34^a adapted to engage contact points 34^b, 34^b whenever the solenoid is energized to move the core. It will be seen that the switch is closed whenever current flows through the solenoid. Whenever current is interrupted either by opening the switch 79 or by the accidental or intentional removal of the trolley from its wire, or by the blowing of the fuse 72 the switch is automatically opened.

Whenever the switch 34 is closed and the motor 45 is being driven, the said motor acts as a generator to produce current to charge the battery 25. Current will flow from the armature to the brush 45'', to the point 81, to the brush K^4 , the contact section G and the brush K^5 ; from the brush K^5 the current will flow through the charging resistance 32, through the contact bar 34^a of the automatic switch 34 to the brush E^{13} and the brush E^{11} ; from the brush E^{11} the current will flow through the ampere-hour meter, the fuse 80, the plug and socket device 69 to the positive connection of the battery 25; from the negative connection of the battery 25 the current will flow through the plug and socket device 70, through the fuse 82 to the point 83 and to the brush E^{12} ; from the brush E^{12} the current will flow to the brush E^{14} and back to the commutator and armature 45 through the brush 45'. If at any time the trolley flies off from the wire or the fuse 72 is blown, the battery charging circuit will be at once opened to prevent the battery discharging itself directly into the motor 45 to the injury of one or both of them.

In order that the electric circuits may be easily traced, I give below a chart or table indicating the points through which the current successively flows with the cylinder 57 in the "trolley-ahead" position. In the first column is indicated the circuit at starting and in the second column is indicated the circuit when the controller is in full run-

ning position. In the third column is indicated the battery charging circuit.

When the locomotive is to be operated in the reverse direction on current received from the trolley wire, the operator throws the handle 59 to the "trolley-reversed" position thus bringing the contacts B into engagement with the brushes E. The path of the current is similar to that before described with the exception that it passes in the reverse direction through the commutator and armature 44. The battery charging circuit is modified for the reason that the commutator and armature 45 rotate in the reverse direction, the brush 45' being the positive brush instead of the brush 45'' as previously.

The following chart or table indicates

clearly the several circuits. The first column indicates the circuit at starting and in the second column is indicated the circuit when the controller is in full running position. In the third column is indicated the battery charging circuit.

"Trolley-reversed," (contacts B engaged.)

When the locomotive is to be operated independently of the trolley wire, the operator throws the handle 59 to the "battery-ahead" position bringing the contacts D into engagement with the brushes of the series E. In this position the connection to the trolley mechanism and through the commutator and armature 44 are entirely broken. The current flows from the positive connection of the battery through the plug and socket device 69, the fuse 80 and the ampere-hour meter 71 to the brush E³; from the brush E² to the brush E², the point 73, the coils 63 and 64 and the brush K¹; from the brush K¹ to the section F, the

brush K², the brush K¹², the section H and the brush K¹¹ to the point 74; from the point 74 current passes through the resistance 31 to the point 75 and from the point 75 through the brushes E⁵ and E⁶ to the motor brush 45"; from the motor brush 45" the current passes through the commutator and armature 45 and the brush 45' to the brushes E¹¹ and E⁸; from the brush E⁸ the current passes through the field coils 48 and 48' to the point 76; from the point 74 a shunt current passes through the coils 49 and 49' to the point 76; from the point 76 the current passes to the brush E⁹, the brush E¹² and back to the negative connection of

the battery through the point 83, the fuse 82 and the plug and socket device 70. The brushes L^1 and L^2 are connected by one of the contacts of the series B and in this way the circuit is completed through the lamps 30, 30 which are positioned, respectively, in the headlights 28.

The circuits are indicated on the following chart or table, the circuit for starting the 10 motor being indicated in the first column and the circuit during running is indicated in the second column.

"Battery-ahead," (contacts D engaged.)

"battery-reversed" position which brings the 65 contacts A into engagement with the brushes of the series E. The path of the current will be similar to that before described with the exception that it will pass in the reverse direction through the commutator and 70 armature 45.

The following chart or table indicates the circuits. In the first column the circuit for starting the motor being indicated, and the circuit during running is indicated in the 75 second column.

"Battery-reversed," (contacts A engaged.)

When the locomotive is to be operated in the reverse direction independently of the trolley wire, the handle 59 is moved to the

From the foregoing description it will be clear that I have provided a locomotive adapted to run either on a high voltage

trolley wire current or a low voltage battery current. And it will furthermore be clear that in the preferred form of the invention as herein described this result has been accomplished without adding greatly to the size or weight of the motor equipment. A locomotive embodying my invention can be used at will either with the trolley or without it and the battery can be charged at any time when the trolley is on the wire whether the locomotive as a whole be in operation or not in operation. The automatic switch 34 provides not only a convenient means whereby the operator can complete the charging circuit of the battery, but also provides a reliable safety means for automatically protecting the battery and motor against injury.

What I claim is:—

1. In an electric locomotive, the combination with the main frame and the driving wheels, of a trolley mechanism, a storage battery, a motor connected with the wheels and adapted to utilize high voltage current from the trolley mechanism, a second motor connected with the wheels and adapted to utilize low voltage current from the battery, and a controller comprising a set of contacts adapted to introduce starting resistance and four sets of distributing contacts movable independently of the resistance contacts and adapted respectively to connect the trolley mechanism and the resistance contacts in circuit with the high voltage motor to turn it in either direction and to connect the battery and the resistance contacts in circuit with the low voltage motor to turn it in either direction.

2. In an electric locomotive, the combination with the main frame and the driving wheels, of a trolley mechanism, a storage battery, a motive mechanism connected with the wheels and comprising a single set of field poles and a single rotor having two commutators and two sets of armature windings connected respectively thereto, one winding being adapted to utilize high voltage current from the trolley mechanism and the other being adapted to utilize low voltage current from the battery, and a controller comprising a set of contacts adapted to introduce starting resistance and four sets of distributing contacts movable independently of the resistance contacts and adapted respectively to connect the trolley mechanism and the resistance contacts in circuit with the high voltage winding to turn it in either direction and to connect the battery and the resistance contacts in circuit with the low winding motor to turn it in either direction.

3. In an electric locomotive, the combination with the main frame and the driving wheels, of a trolley mechanism, a storage

battery, a motor connected with the wheels 65 and adapted to utilize high voltage current from the trolley mechanism, a second motor connected with the wheels and adapted to utilize low voltage current from the battery, and electrical connections including a controlling switch having four positions adapted as follows: (1st) to connect the first motor with the trolley mechanism to cause rotation in one direction, (2nd) to connect the first motor with the trolley mechanism 70 to cause rotation in the other direction, (3rd) to connect the second motor with the battery to cause rotation in the first said direction, and (4th) to connect the second motor with the battery to cause rotation in 80 the second said direction.

4. In an electric locomotive, the combination with the main frame and the driving wheels, of a trolley mechanism, a storage battery, a motor connected with the wheels 85 and adapted to utilize high voltage current from the trolley mechanism, a second motor connected with the wheels adapted to utilize low voltage current from the battery, and means for changing the electrical connections between the battery and the second motor whereby the latter may be used as a generator to charge the battery, and a controller comprising contacts adapted to introduce starting resistance into the circuit 90 of the first motor and other contacts adapted to complete the battery charging circuit only when the starting resistance is cut out of the motor circuit.

5. In an electric locomotive, the combination with the main frame and the driving wheels, of a trolley mechanism, a storage battery, a motive mechanism connected with the wheels and comprising a single set of field poles and a single rotor having two 105 commutators and two sets of armature windings connected respectively thereto, one winding being adapted to utilize high voltage current from the trolley mechanism and the other being adapted to utilize low voltage current from the battery, means for changing the electrical connections between the battery and the second set of winding and the second commutator whereby they may be used to generate current to charge 110 the battery, and a controller comprising contacts adapted to introduce starting resistance into the circuit of the first motor and other contacts adapted to complete the battery charging circuit only when the 120 starting resistance is cut out of the motor circuit.

6. In an electric locomotive, the combination with the main frame and the driving wheels, of a trolley mechanism, a storage 125 battery, a motor connected with the wheels and adapted to receive current from the trolley mechanism, a motor-generator con-

nected with the wheels and adapted to receive current from the battery or to supply current thereto, a circuit changing means connected with the motor-generator and the 5 battery, an opening switch in the battery supply circuit, and electromagnetic means receiving current from the trolley mechanism for holding the switch closed.

7. In an electric locomotive, the combination with the main frame and the driving 10 wheels, of a trolley mechanism adapted to engage and run along a conductor wire, a storage battery, a motor connected with the wheels, conductors for transmitting current 15 from the trolley mechanism to the motor, a manually operable clutch between the motor and the wheels, and a motor-generator mechanically connected with the said motor and adapted to receive current from the 20 battery for driving the wheels through the said clutch or to supply current to the battery to charge it when driven by the said motor, the said clutch making it possible for the motor while receiving current from the trolley 25 mechanism and the trolley wire to drive the wheels or to drive the motor generator independently of the wheels.

8. In an electric locomotive, the combination with the main frame and the driving 30 wheels, of a trolley mechanism, a storage battery, a motor connected with the wheels and adapted to receive current from the trolley mechanism, a motor-generator connected 35 with the wheels and adapted to receive current from the battery or to supply current thereto, and electrical conductors including a controlling switch having positions adapted as follows: (1st) to connect the motor with the trolley mechanism through a starting 40 resistance to cause rotation and to connect the motor-generator with the battery to charge it after the starting resistance has been cut out of the motor circuit, and (2nd) to connect the motor-generator with the battery 45 to cause rotation.

9. In an electric locomotive, the combination with the main frame and the driving 50 wheels, of a trolley mechanism, a storage battery, a motor connected with the wheels and adapted to receive current from the trolley mechanism, a motor-generator connected 55 with the wheels and adapted to receive current from the battery or to supply current thereto, an electrical conductor including a controlling switch having four positions adapted as follows: (1st) to connect the motor with the trolley mechanism to cause rotation in one direction and to simultaneously connect the motor-generator with the 60 battery to charge it, (2nd) to connect the motor with the trolley mechanism to cause rotation in the other direction and to simultaneously connect the motor-generator with the battery to charge it, (3rd) to connect the

motor-generator with the battery to cause 65 rotation in one direction, and (4th) to connect the motor-generator with the battery to cause rotation in the other direction.

10. In an electric locomotive, the combination with the main frame and the driving 70 wheels, of a trolley mechanism, a storage battery, a motor connected with the wheels and adapted to receive current from the trolley mechanism, a motor-generator connected 75 with the wheels and adapted to receive current from the battery or to supply current thereto, electrical conductors including a controlling switch having positions adapted as follows: (1st) to connect the motor with the trolley mechanism to cause rotation and 80 to connect the motor-generator with the battery to charge it and (2nd) to connect the motor-generator with the battery to cause rotation, an automatically opening switch in the charging circuit through the motor-generator and the battery, and means dependent on the flow of current through the 85 said trolley mechanism for holding the said switch closed.

11. In an electric locomotive, the combination with the main frame and the driving 90 wheels, of a trolley mechanism, a storage battery, a motor connected with the wheels and adapted to receive current from the trolley mechanism, a motor-generator connected 95 with the wheels and adapted to receive current from the battery or to supply current thereto, electrical conductors including a controlling switch having positions adapted as follows: (1st) to connect the motor with the trolley mechanism to cause rotation and 100 to simultaneously connect the motor-generator with the battery to charge it and (2nd) to connect the motor-generator with the battery to cause rotation, an automatically opening switch in the charging circuit through the motor-generator and the battery, means dependent on the flow of current through the 105 said trolley mechanism for holding the said switch closed, and manually operable 110 means for causing the said switch to open.

12. In an electric locomotive, the combination with the main frame and the driving 115 wheels, of a trolley mechanism, a storage battery, a motor connected with the wheels and adapted to receive current from the trolley mechanism, a motor-generator connected 120 with the wheels and adapted to receive current from the battery or to supply current thereto, electrical conductors including a controlling switch having positions adapted as follows: (1st) to connect the motor with the trolley mechanism through a starting resistance to cause rotation and to connect the motor-generator with the battery to charge 125 it after the resistance has been cut out of the motor circuit and (2nd) to connect the motor-generator with the battery to cause ro-

tation, an automatically opening switch in the charging circuit through the motor-generator and the battery, and means dependent on the flow of current through the said trolley mechanism for holding the said switch closed.

In testimony whereof, I affix my signature, in presence of two witnesses.

JOHN H. FLORY.
